Assistant Examiner — Kendra L Hebel

(57) CLAIM

The ornamental design for a vegetable chopper and slicer cover as shown and described.

DESCRIPTION

1. Vegetable chopper and slicer cover

1.1 : Perspective

1.2 : Perspective

1.3 : Front

1.4 : Back

1.5 : Left

1.6 : Right

1.7 : Top

1.8 : Bottom

1.9 : Exploded

1.10 : Perspective view in a first usage state

1.11 : Perspective view in a second usage state

The parts shown by means of dash-dash broken lines in the reproductions are not part of the claimed design.

1 Claim, 11 Drawing Sheets
